UNITED STATES PATENT OFFICE.

JOSEPH D. FERRY, OF MCKEESPORT, PENNSYLVANIA.

ENGINE.

SPECIFICATION forming part of Letters Patent No. 773,490, dated October 25, 1904.

Application filed September 25, 1903. Serial No. 174,643. (No model.)

To all whom it may concern:

Be it known that I, JOSEPH D. FERRY, a citizen of the United States, residing at McKeesport, in the county of Allegheny, State 5 of Pennsylvania, have invented certain new and useful Improvements in Engines, of which the following is a specification, reference being had therein to the accompanying drawings.

10 This invention relates to an engine, and particularly to a structure adapted for use with an explosive charge or with a continuous pressure of steam, air, or other motive agent.

15 The invention has for an object to provide means whereby the controlling-valves for the power-cylinder may be operated to effect a proper feed and exhaust for the explosive action in the cylinders or by shifting the parts the operation of the valve will be altered to 20 adapt the engine for use with a continuous pressure of steam or air.

25 A further object of the invention is to provide compressing-cylinders operatively connected with the shaft driven from the power-cylinders and operating in unison with the said cylinders, so as to place the motive agent under suitable compression prior to its introduction into the power-cylinders.

30 Another object of the invention is to provide an improved construction of valve and casing with means for retaining the valve under tension and adapted to effect a feeding and exhaust to the power-cylinders.

35 The invention also presents novel details of construction in the mounting of the levers by which the power is communicated to the cylinder-valves and also in the shiftable means by which the cam and eccentric coöperating with these levers are adapted to be moved laterally, so that either one thereof will be in 40 operative position.

45 Other and further objects and advantages of the invention will be hereinafter set forth and the novel features thereof defined by the appended claims.

50 In the drawings, Figure 1 is a side elevation of the engine with parts in section. Fig. 2 is a plan thereof with parts in section. Fig. 3 is a central vertical longitudinal section through one set of the power and compress-

ing cylinders on line 3 3 of Fig. 2. Fig. 4 is a detail horizontal section on the line 4 4 of Fig. 5. Fig. 5 is a vertical section on the line 5 5 of Fig. 3. Fig. 6 is a similar section on the line 6 6 of Fig. 3. Fig. 7 is a vertical section showing the valve-operating cam. Fig. 8 is an elevation showing the valve-operating eccentric and cam together. Fig. 9 is an end view of one of the rotary cylinder-valves. Fig. 10 is a similar view of the oscillating plate coöperating with the end of this valve. Fig. 11 is a detail enlarged horizontal section showing the valve-holding means assembled. Fig. 12 is a plan of the top of the valve-chambers for the power-cylinders with the cover-plate removed. Fig. 13 is a vertical section thereof on the line 13 13 of Fig. 12. Fig. 14 is a detail plan showing the shifting mechanism for the cam and eccentric. Fig. 15 is a detail elevation of the cam and eccentric. Fig. 16 is a detail perspective of the valve-lever coöperating therewith. Fig. 17 is a detail elevation of one end of the compressing-cylinders, showing the ports leading therefrom. Fig. 18 is an edge view of the piston-packing. Fig. 19 is a side elevation thereof. Fig. 20 is a detail elevation with parts in section and separated from each other, and Fig. 21 is an elevation of the shift-bar.

Like letters of reference refer to like parts in the several figures of the drawings.

The letter A designates the power-shaft, supported within a suitable casing, as shown at A', which may be of any desired configuration and closed, if desired, by a cover-plate A², which in Fig. 2 is shown as removed. This shaft is provided at suitable points with one or more crank-arms A³, depending upon the number of cylinders used in connection with the engine. While two power-cylinders B are shown herein, together with two coöperating compressing-cylinders C, still it will be obvious that single power and compressing cylinders could be used or a greater number assembled in connection with the driving-shaft if found desirable. This shaft is also provided at one end with the usual balance or fly wheel A⁴ and may be supported centrally of its length, if found desirable, by means of a standard and bearing A⁵. Within each of

the power-cylinders B a piston B' is disposed, which is connected by means of the piston-rod B² with the cross-head B³, which is provided with a sliding bearing-block B⁴, journaled upon the crank-arm A³. The parallel members of this cross-head are connected together at their opposite ends in any desired manner—for instance, by means of the bolt B⁵, passing through a spacing-sleeve B⁶, disposed between the ends of the head, as shown in Figs. 1 and 3. The piston-rod may be connected to this head in any desired manner—for instance, by means of the tapered end portion B⁷, through which the wedge or cotter pin B⁸ is adapted to pass. It will be understood that the cylinders and pistons herein-after described are similar in construction, and therefore it is only necessary to specifically describe one thereof.

Upon the opposite side of the power-shaft from the power-cylinder is the compressing-cylinder C, which is provided with a piston C', having a rod C², connected with the cross-head B³ by means of the tapered end C³ and cotter-pin C⁴, whereby in the rotation of the crank-arm the block B⁴ reciprocates in the cross-head and produces a simultaneous movement of the pistons, or as if the pistons were connected to a continuous shaft. The compressing-cylinder may be of any desired construction; but a desirable form thereof is illustrated herein, in which the inlet-port D is provided at the lower portion thereof and communicates with the chamber D', Fig. 6, which is provided with suitable check-valves D² and communicates with each of the cylinders at the ends thereof by means of the passage D³, as shown in Fig. 17. The casing opposite each of these valves is provided with an aperture and plug D⁴, by which access can be obtained thereto. A set of the inlet and outlet valves D² is provided at each end of the compressing-cylinder, so that the compressing operation is performed during both strokes of the piston therein, while the compressed fluid is discharged from the outlet D⁵, disposed between the two cylinders, and conducted by the pipe D⁶, communicating with the power-cylinder. The pipe D⁶ communicates with the longitudinally-extending passage E', disposed between the two power-cylinders, and communicates at each end with the valve-casings E², which extend transversely of the cylinders, one at each end thereof. In the walls of this inlet-passage E' suitable oil-tubes E³ extend downward and communicate with the valve-chambers for the purpose of lubricating the same, as shown in Figs. 5 and 12. These valve-casings are provided with inlet-ports E⁴ and exhaust-ports E⁵, the latter of which communicate, through the passage E⁶, extending transversely of the cylinders, with the exhaust-port E⁷ at one end of the casing. Suitable oil tubes or passages E⁸ extend downward through this exhaust-chamber and communi-

cate with each of the cylinders through the opening E⁹ for the purpose of lubricating the same and, if desired, may be closed at their upper ends by means of plugs E¹⁰.

Within each of the valve-casings E² a sleeve F is secured and provided with a tapered interior face, preferably largest at its inner end. This sleeve may be secured in position in any desired manner—for instance, by means of threads F' at its inner end engaging similar threads on the casing adjacent to the inlet-passage E'. Each of the sleeves is provided with an inlet-port F² and an exhaust-port F³, which when the sleeves are secured in position are in alinement with similar ports in the casing. (See Fig. 5.) Disposed within these sleeves are the valves G of tapering or conical shape, adapted to fit snugly the interior of the sleeves F, and the valves are each open at their inner end, communicating with the inlet-passage E', while the body of the valves is provided at one side with ports G', adapted to communicate with the inlet-ports in the sleeve and casing, while the periphery of the valve is provided with a concaved portion G², Fig. 9, by which communication may be established between the inlet-port and the exhaust-passage. The outer end of the valve G is closed, as at G³, and provided with a slot G⁴, Fig. 9, having overhanging walls behind which the head G⁵, carried by the adjusting-bolt G⁶, is adapted to fit. The end of the valve is also provided with lugs G⁷, disposed at opposite points and adapted to pass through apertures H' in the bearing-plate H, Fig. 10, which is thus connected to the valve and provided with a central threaded opening H², through which the bolt G⁶ passes. This plate is also provided with a crank-pin H³, by which connection is made with the valve-operating mechanism. The plate H is formed with the proper bearing-surface upon its interior face and adapted to contact with balls H⁴, disposed within a shell or casing H⁵, which is suitably provided, as at H⁶, to permit the movement of the valve independently of the shell. These parts are suitably clamped and held together by means of the nut H⁷, disposed upon the bolt G⁶, while this bolt is further provided with an angular wrench-hold G⁸, by which it may be adjusted to draw the valve tightly into contacting position with its sleeve. In order to form the proper bearing for the outer end of the bolt G⁶ in the oscillation of the valve, the bracket-arm I, Fig. 11, is interiorly threaded and the bearing-screw I' inserted therein and provided with a lock-nut I², threaded thereon. The inner end of this screw is recessed, as at I³, and suitable bearing-balls I⁴ may be provided to form a roller-bearing between the base of this recess and the bearing-face I⁵, carried by the outer end of the bolt G⁶.

Surrounding the power-cylinders are the usual water-jackets I⁷, which are supplied from any desired source—for instance, the connec-

tion I⁸ at the top of the cylinder (see Figs. 2 and 13) and the aperture I⁹ in the lower portion of the casing between the cylinders.

When used as an explosive-engine, any desired form of igniting device may be applied—for instance, as indicated at I¹⁰ in Fig. 3.

For the purpose of oscillating the valves controlling the supply and exhaust of the power-cylinders the power-shaft A is provided 10 with a valve-controlling device J, which comprises an eccentric J' for operation with steam or air and a cam J² for the explosive action, as shown in Figs. 7, 8, and 15. These parts may be separately formed, but are preferably 15 connected together and suitably mounted upon the power-shaft by any desired means—for instance, the keyway J³—so as to be shifted when it is desired to change the motive agent for the engine by any desired mechanism, a 20 form of which will be hereinafter described. At opposite sides of the valve-controlling device J are levers J⁴, pivotally mounted upon lugs J⁵, Fig. 1, extending from the engine-frame, by means of the bearing J⁶ at their lower 25 ends and shown in detail by Fig. 16. Above this bearing the bearing J⁷ is provided and adapted to receive an antifriction-roller J⁸ for contacting with the shifting device, while at the upper portion an eye or bearing J⁹ is 30 formed for the purpose of connecting the rod K, which extends to the valve. The levers J⁴ at opposite sides of the shifting device are connected together by springs K', which extend from the cross-plate K², carried by the 35 upper end of the levers, and are permanently connected to one of said plates, while the plate upon the opposite lever is provided with a threaded bolt K³, adjustable therein and adapted to be held in its adjusted position by means 40 of lock-nuts K⁴, Fig. 16. One of these rods K extends from each of the levers, and a set of these levers is applied at each side of the engine, so as to independently control each of the four valves used in connection with the 45 two cylinders shown. The valve-rods K may be connected with the crank-pins H³, by which the valves are oscillated in any desired manner—for instance, as shown in Fig. 1—by means of the clip-plate K⁵, embracing the pin 50 and held upon the threaded end of the rod by means of opposite nuts K⁶. The connection of the rods K to the opposite levers J permits the alternate movements of the valves for effecting an independent pressure and exhaust 55 connection at each end of each piston. These pistons may be provided with any desired form of packing, a preferred construction of which is shown in Figs. 18, 19, and 20. The piston B is provided with a circumferential 60 groove L, within which an angular plate L' is disposed and formed in a series of separated segments. Upon the flange L² of this plate the segments L³ of the bearing-ring are disposed, and one end of each of these segments 65 is connected to the angular ring at L⁴ in any

desired manner, so that the free end of the segments L³ may overlap the joints between the sections of the angular body and permit an expansion thereof without leaving a space between the ends of the sections. The sections of the packing-ring L³ are each provided at each end with an aperture L⁵, while a spring L⁶ is disposed within the adjacent apertures, thus normally separating the segments of the bearing-ring, so as to permit a slight compression thereof and insure a close fit with the walls of the cylinders. This packing is shown in connection with the pistons in the power-cylinders; but it may also be used as well upon the compressing-pistons if found 70 desirable.

Any desired means may be employed for shifting the cam-and-eccentric device when the motive power of the engine is to be changed from an explosive to a constant pressure, or vice versa, and as illustrating a desirable means thereof I have provided a shifting-bar M, Fig. 21, having at its opposite ends sockets M', within which the free ends of levers M² are pivotally mounted by means of 85 a pin M³. These levers M² extend beneath the power-shaft and controlling device and are mounted upon a pivot M⁴, secured to the base by means of a stud M⁵, bolted thereto, Fig. 1, while the ends of the levers M² beneath the shifting device are provided with a sleeve M⁶, adapted to receive a pintle M⁷, extending downward from the yoke or connecting device M⁸, which is adapted to be secured to the shifting device—for instance, by 90 embracing a groove between the cam and eccentric thereon—while the pivotal mounting of the connector permits the free movement of the controlling device upon the power-shaft. For the purpose of shifting the bar 100 M an angularly-disposed solid arm M⁹ is provided at one end thereof and adapted to engage a crank-pin N, carried upon a disk N', the shaft N² of which is extended beyond the frame through a suitable stuffing-box N³ and 105 provided at its free end with an operating-lever N⁴. It will be seen that the oscillation of the shaft N² will shift the bar M, thus simultaneously moving the controlling devices for the valves carried upon the power-shaft 110 through the medium of the pivoted levers at the opposite ends thereof.

In the operation of the invention in case steam or air are to be used as the motive agent the same enters compressing-cylinder 120 in the movement of the piston therein and is alternately received and further compressed in the movement of this piston. It passes thence through the ports at the ends of the cylinder to the conducting-pipe and thence 125 to the valve-chests above the power-cylinder and is fed to the interior of the valves, through which it passes in the oscillation thereof during the alternate charging of the opposite ends of the power-cylinder, by which pres- 130

sure is applied to both sides of the piston therein. These valves carry the charge under constant pressure or compression and discharge it to the cylinder in their oscillation, while the exhaust from the cylinder passes around the valve-casing and through the passages heretofore described. If the engine is to be used with gas or any similar explosive fluid, the oscillation of the valves is suitably timed for that purpose by bringing the cam carried by the controlling device in alinement with the levers connected to the valve-operating rods, while an igniting device is also provided in connection with the power-cylinder. If it be found desirable to use the engine with steam, air, or other fluid under compression, the controlling device may be moved upon the power-shaft by the means hereinbefore described, so as to bring the eccentric thereon into alinement with the valve-controlling levers, thus securing the desired timing of the inlet and exhausting of the charges to the opposite ends of the cylinder in order that power may be applied at one end of each cylinder during each stroke of the piston. With the parts in the position shown in Fig. 3 it will be seen that the right end of the cylinder is receiving a charge while the left end is in connection with the exhaust, so that the movement of the piston in the cylinder operates the power-shaft and the controlling device carried thereby, so that the valves are reversed in position as the piston approaches the passage at the left end of the cylinder, thus applying the charge at that point and restoring the piston to its initial position. (Shown in Fig. 3.) The power is communicated from the piston-rod to the crank-shaft by means of the cross-head, which also carried the compressing-piston at the opposite side of the power-shaft, whereby the compressing-piston maintains the charge for the engine under constant pressure, by which the most desirable operation is secured both with an explosive and with a non-explosive motive agent. The construction of the valves for the power-cylinder also permits the same to be tightly fitted within their sleeves and held there to prevent leakage, while they are mounted for free oscillation, as before described.

Two power and compressing cylinders are shown in the present application; but it will be obvious that the functions of the invention could be performed by a single set thereof; but in the use of two cylinders greater power is secured and a consequent economy of fuel, while the construction of the valve-casing for feeding this fuel permits the introduction of the same at the open end of the valves and exhaust-passage extending longitudinally between the valves.

It will be obvious that changes may be made in the details of construction and configuration without departing from the spirit of the

invention as defined by the appended claims and that different forms of cross-heads may be used for connecting the power and compression pistons for simultaneous movement.

Having described my invention and set forth its merits, what I claim, and desire to secure by Letters Patent, is—

1. In an engine, a power-cylinder, a piston therein connected to the power-shaft, a plurality of valves for said cylinder, a plurality of valve-controlling devices connected to the power-shaft for independently timing the movement of said valves, and means at the opposite sides of said devices each connected to an independent valve to operate the same. 80

2. In an engine, a power-cylinder, a piston therein connected to the power-shaft, a plurality of valves for said cylinder, a valve-controlling device connected to the power-shaft for timing the movement of said valves, and means held under tension in contact with the opposite sides of said controlling device and each connected to an independent valve to operate the same. 85

3. In an engine, a power-cylinder, a piston therein connected to the power-shaft, a plurality of valves for said cylinder, a valve-controlling device connected to the power-shaft for timing the movement of said valves, levers held under tension in engagement with the opposite sides of said controlling device, and independent valve-rods extending from the free end of each lever to each valve. 95

4. In an engine, a power-cylinder, a piston therein, valves at the opposite ends of said cylinder, a power-shaft connected to said piston, a valve-controlling device upon said power-shaft, levers at the opposite sides of said device, pivoted at one side of said device and connected together by tension-springs at the opposite side thereof, and connecting-rods from said levers to operate said valves. 100 105

5. In an engine, a power-cylinder, a piston therein, valves at the opposite sides of said cylinder, a power-shaft connected to said piston, a plurality of valve-controlling devices upon said power-shaft, pivoted levers at the opposite sides of one of said devices, connecting-rods from said levers to operate said valves, shifting means carried by the controlling devices and adapted to throw one thereof into the path of said levers. 110 115

6. In an engine, a power-cylinder, a piston therein, valves at the opposite sides of said cylinder, a power-shaft connected to said piston, a plurality of valve-controlling devices upon said power-shaft, pivoted levers at the opposite sides of one of said devices, connecting-rods from said levers to operate said valves, shifting means carried by the controlling devices and adapted to throw one thereof into the path of said levers, and a tension-spring connecting the free ends of said levers to throw the same toward each other. 120 125

7. In an engine, a power-cylinder, a piston 130

therein, valves at the opposite sides of said cylinder, a power-shaft connected to said piston, a plurality of valve-controlling devices upon said power-shaft, pivoted levers at the 5 opposite sides of one of said devices, connecting-rods from said levers to operate said valves, shifting means carried by the controlling devices and adapted to throw one thereof into the path of said levers, a tension-spring 10 connecting the free ends of said levers to throw the same toward each other, a cross-head carried by the power-shaft and connected to the piston in the power-cylinder, a compressing-cylinder at the opposite side of the 15 power-shaft, a piston therein connected with said cross-head, and a connecting-passage from the compressing-cylinder to said valves.

8. In the engine, a power-cylinder, valve-chambers extending transversely at its opposite ends, tubular valves mounted to oscillate in said chambers and provided with inlet-ports to communicate with the cylinder, an intake-passage communicating with the open end of said valves, and an exhaust-passage 25 formed at one side of said valves.

9. In an engine, a power-cylinder, valve-chambers extending transversely at its opposite ends, tubular valves mounted to oscillate in said chambers and provided with inlet-30 ports to communicate with the cylinder, an intake-passage communicating with the open end of said valves, an exhaust-passage formed at one side of said valves, means for drawing said valves longitudinally within their casing, 35 and means connected to the outer end of the valves for oscillating the same.

10. In an engine, a plurality of power-cylinders disposed parallel to each other, valve-casings extending transversely of said cylinders 40 at the opposite ends thereof and provided with an inlet-opening at their mid-length, an exhaust-chamber extending transversely of the cylinders between the valve-casings, a power-shaft, and pistons carried thereby disposed 45 within said cylinders and connected to crank-arms upon said shaft.

11. In an engine, a plurality of power-cylinders disposed parallel to each other, valve-casings extending transversely of said cylinders 50 at the opposite ends thereof and provided with an inlet-opening at their mid-length, an exhaust-chamber extending transversely of the cylinders between the valve-casings, a power-shaft, pistons carried thereby disposed within 55 said cylinders and connected to crank-arms upon said shaft, a slide-block carried by said crank-arm, and a cross-head comprising parallel ways within which said block reciprocates.

60 12. In an engine, a plurality of power-cylinders disposed parallel to each other, valve-casings extending transversely of said cylinders at the opposite ends thereof and provided with an inlet-opening at their mid-length, an exhaust-chamber extending transversely of the 65

cylinders between the valve-casings, a power-shaft, pistons carried thereby disposed within said cylinders and connected to crank-arms upon said shaft, a slide-block carried by said crank-arm, a cross-head comprising parallel ways within which said block reciprocates, parallel compression-cylinders, pistons therein, and piston-rods extending from the compressing-pistons to the cross-head. 70

13. In an engine, a plurality of power-cylinders disposed parallel to each other, valve-casings extending transversely of said cylinders at the opposite ends thereof and provided with an inlet-opening at their mid-length, an exhaust-chamber extending transversely of the 80 cylinders between the valve-casings, a power-shaft, pistons carried thereby disposed within said cylinders and connected to crank-arms upon said shaft, a slide-block carried by said crank-arms, a cross-head comprising parallel ways within which said block reciprocates, parallel compression-cylinders, pistons therein, piston-rods extending from the compressing-pistons to the cross-head, valves 85 within said casing, controlling means carried at the opposite ends of said power-shaft, independent levers adapted to contact with said controlling means, and independent valve-rods extending from each of said levers to the valve controlled thereby. 90

14. In an engine, a plurality of power-cylinders disposed parallel to each other, valve-casings extending transversely of said cylinders at the opposite ends thereof and provided with an inlet-opening at their mid-length, an exhaust-chamber extending transversely of the cylinders between the valve-casings, a power-shaft, pistons carried thereby disposed within said cylinders and connected to crank-arms upon said shaft, a slide-block carried by 100 said crank-arms, a cross-head comprising parallel ways within which said block reciprocates, parallel compression-cylinders, pistons therein, piston-rods extending from the compressing-pistons to the cross-head, valves 105 within said casing, shifting means carried at the opposite ends of said power-shaft, independent levers adapted to contact with said shifting means, independent valve-rods extending from each of said levers to the valve 110 controlled thereby, a plurality of contact-faces carried by the controlling means, and a shifting-lever for simultaneously moving the controlling means upon the power-shaft for bringing the different faces thereof in contact 115 with said levers. 120

15. In an engine, the combination with a power-cylinder having a port at one end and an exhaust-passage extended therefrom, of a valve-casing communicating therewith, a sleeve secured within said casing and provided with ports communicating with the cylinder and the exhaust-passage therefrom, a cylindrical valve having a tapering periphery and an open end to provide an interior inlet-pas- 125 130

sage with a port in one wall, a closed head at one end of said valve, and means for engaging said head and drawing said valve longitudinally within the casing.

5 16. In an engine, the combination with a power-cylinder having a port at one end and an exhaust-passage extended therefrom, of a valve-casing communicating therewith, a sleeve secured within said casing and provided 10 with ports communicating with the cylinder and the exhaust-passage therefrom, a cylindrical valve having a tapering periphery and an open end to provide an interior inlet-passage with a port in one wall, a closed head at 15 one end of said valve, a threaded shaft having a head to engage a socket at the head end of said valve, and a bearing for said shaft for drawing the same outwardly.

17. In an engine, the combination with a 20 power-cylinder having a port at one end and an exhaust-passage extended therefrom, of a valve-casing communicating therewith, a sleeve secured within said casing and provided with ports communicating with the cylinder 25 and the exhaust-passage therefrom, a valve having a tapering periphery and an interior inlet-passage with a port in one wall, a threaded shaft having a head to engage a socket at the outer end of said valve, a bearing for said 30 shaft for drawing the same outwardly, projecting lugs upon the outer end of the valve, a disk having apertures to fit said lugs and a crank-pin extending laterally therefrom, and means for operating said pin from the engine 35 crank-shaft.

18. In an engine, the combination with a power-cylinder having a port at one end and an exhaust-passage extended therefrom, of a valve-casing communicating therewith, a 40 sleeve secured within said casing and provided with ports communicating with the cylinder and the exhaust-passage therefrom, a valve having a tapering periphery and an interior inlet-passage with a port in one wall, a threaded 45 shaft having a head to engage a socket at the outer end of said valve, a bearing for said shaft for drawing the same outwardly, projecting lugs upon the outer end of the valve, a disk having apertures to fit said lugs and 50 a crank-pin extending laterally therefrom, a casing within which said disk is disposed, bearing-balls interposed between the disk and casing, and means for operating said pin from the engine crank-shaft.

55 19. In an engine, the combination with a power-cylinder having a port at one end and an exhaust-passage extended therefrom, of a valve-casing communicating therewith, a sleeve secured within said casing and provided 60 with ports communicating with the cylinder and the exhaust-passage therefrom, a valve having a tapering periphery and an interior inlet-passage with a port in one wall, a threaded 65 shaft having a head to engage a socket at the outer end of said valve, a bearing for said

shaft for drawing the same outwardly, projecting lugs upon the outer end of the valve, a disk having apertures to fit said lugs and a crank-pin extending laterally therefrom, a casing within which said disk is disposed, 70 bearing-balls interposed between the disk and casing, a fixed bracket between the outer end of the said threaded shaft, an adjusting-screw disposed therein and provided with a bearing-recess for the outer end of said shaft, and 75 means for operating said pin from the engine crank-shaft.

20. In an engine, the combination with a power-cylinder having a port at one end and an exhaust-passage extended therefrom, of 80 a valve-casing communicating therewith, a sleeve secured within said casing and provided with ports communicating with the cylinder and the exhaust-passage therefrom, a valve having a tapering periphery and an interior 85 inlet-passage with a port in one wall, a threaded shaft having a head to engage a socket at the outer end of said valve, a bearing for said shaft for drawing the same outwardly, projecting lugs upon the outer end of the valve, 90 a disk having apertures to fit said lugs and a crank-pin extending laterally therefrom, a casing within which said disk is disposed, bearing-balls interposed between the disk and casing, a fixed bracket between the outer end 95 of the said threaded shaft, an adjusting-screw disposed therein and provided with a bearing-recess for the outer end of said shaft, bearing-balls disposed between the end of said shaft, the base of the recess, a lock-nut for said adjusting-screw, and a wrench-hold upon said threaded shaft, and means for operating said pin from the crank-shaft.

21. In an engine, a power-cylinder, a valve having a crank-pin connected thereto for oscillation therewith, a power-shaft, a valve-controlling device located thereon, a lever pivotally mounted below said shaft and provided between its ends with a contact-roller to engage said device, and a valve-rod extending 105 from the upper end of said lever above said shaft to said crank-pin.

22. In an engine, a power-cylinder, a valve having a crank-pin connected thereto for oscillation therewith, a power-shaft, a valve-controlling device located thereon, a lever pivotally mounted below said shaft and provided with a contact-roller to engage said device, a valve-rod extending from said lever to said 110 crank-pin, a clip-plate embracing said crank-pin, and having eyes at opposite ends through which said rod passes, and nuts disposed upon said threaded end of said valve-rod to contact with the opposite faces of said clip.

23. In an engine, a power-cylinder, valves 125 communicating therewith, a power-shaft, a valve-controlling device carried upon said shaft, levers at the opposite sides of said controlling device and pivotally mounted to contact therewith, valve-rods extending from 130

each of said levers to an independent valve for operating the same, a cross-bar upon the upper end of said levers, a tension-spring extending between the bars upon the opposite 5 levers, and an adjusting device carried by one of said cross-bars for varying the tension of said spring.

24. In an engine, a power-cylinder, a power-shaft and piston connected therewith, a valve 10 for said cylinder, a controlling device for said valve comprising a plurality of faces of different outline, means for communicating motion from either of said faces to the valves, a lever mounted beneath said controlling device and 15 connected therewith, a shifting bar for operating said lever, and a shaft provided with a crank-pin for operating said shifting bar.

25. In an engine, a cylinder, a power-shaft and piston connected therewith, valves at the 20 opposite sides of said cylinder, a movable valve - controlling device slidingly mounted upon the opposite ends of said power-shaft, pivoted levers at the opposite ends of the power-shaft mounted upon a stud carried by 25 the engine-frame, a sleeve at the inner end of said levers beneath said controlling devices, a yoke engaging said devices and pivotally mounted in said sleeve, and a shifting bar connecting the outer ends of said levers.

30 26. In an engine, a cylinder, a power-shaft and piston connected therewith, valves at the opposite sides of said cylinder, a movable

valve - controlling device slidingly mounted upon the opposite ends of said power-shaft, pivoted levers at the opposite ends of the 35 power-shaft mounted upon a stud carried by the engine-frame, a sleeve at the inner end of said levers beneath said controlling devices, a yoke engaging said devices and pivotally mounted in said sleeve, a shifting bar connecting the outer ends of said levers, an operating-shaft for said bar mounted in the engine-frame, a disk carried by the inner end of said shaft, an angularly-disposed slotted extension from said shifting bar, a crank-pin from said 45 disk disposed in said slot, and an operating-handle upon the outer free end of said shaft.

27. In an engine, a power-cylinder, a piston therein, a power-shaft connected to said piston, a compression-cylinder at the opposite 50 side of the power-shaft from the power-cylinder and provided with a piston connected with said shaft, and valve-controlled inlet and outlet chambers extending longitudinally of the compression-cylinder and having passages 55 at the upper and lower portions of each end of said compression-cylinder communicating with valve-controlled air-chambers.

In testimony whereof I affix my signature in presence of two witnesses.

JOSEPH D. FERRY.

Witnesses:

JACOB A. STARRETT,
SAMUEL McCORKLE.
